(57) **CLAIM**

The ornamental design for a tote handle with diamond features, as shown and described.

DESCRIPTION

FIG. 1 is a top front perspective view of a tote handle with diamond features;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a reduced scale top front perspective view thereof in environment of use.

A left side elevational view is not shown because it is a mirror image of the right side elevational view shown in FIG. 6.

The ornamental design which is claimed is shown in solid lines in the drawings. The broken lines in the figures depict environmental subject matter only and form no part of the claimed design.
